(57) **CLAIM**

I claim the ornamental design for jeans with stitching pattern, as shown and described.

DESCRIPTION

FIG. 1 is a front view of the jeans with stitching pattern showing my new design; and,

FIG. 2 is a rear view thereof.

The broken lines showing the belt loops, buttons, buttonholes and fly tab are for the purpose of illustrating environmental structure and form no part of the claimed design. The broken lines shown along the bottom and sides of the article form the bounds of the claimed design and form no part of the claimed design. The dashed lines shown on the claimed design are for the purpose of illustration stitching.
